(57) **CLAIM**

The ornamental design for a pallet rack, as shown and described.

DESCRIPTION

FIG. 1 is a perspective view of a pallet rack.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a perspective view of the pallet rack, shown in condition of use.

The broken lines in the figures shown portions of the pallet rack that form no part of the claimed design. Additional broken lines in FIG. 8 show environment and form no part of the claimed design.

The specification includes an appendix, which forms part of the application disclosure and is incorporated herein by reference.
